UNITED STATES PATENT OFFICE.

EDWARD E. BARRETT, OF SPOKANE, WASHINGTON.

ROAD-GRADER.

1,171,084.

Specification of Letters Patent.

Patented Feb. 8, 1916.

Application filed August 12, 1914. Serial No. 856,447.

To all whom it may concern:

Be it known that I, EDWARD E. BARRETT, a citizen of the United States, residing at Spokane, in the county of Spokane and State of Washington, have invented certain new and useful Improvements in Road-Graders, of which the following is a specification, reference being had to the accompanying drawings.

10 This invention relates to new and useful improvements in road drags and the primary object of the invention is to provide an improved device of this character which will effectively remove deep tracks and gullies in a road and completely level the same.

15 A further object of the invention resides in providing an improved drag composed of harrow and leveler sections and still another object resides in providing improved means for the adjustment of the sections so as to dispose the ground treating portions to various positions, as desired.

20 A still further object of the invention resides in providing a drag which is of completely improved construction over the various other road grading devices heretofore known and a still further object resides in providing a device which is simple and durable in construction, inexpensive to manufacture and one which will be very efficient and useful in operation.

25 With these and other objects in view, the invention consists in the novel features of construction, combination and arrangement of parts as will be hereinafter referred to and more particularly pointed out in the specification and claims.

30 In the accompanying drawings forming a part of this application, Figure 1 is a plan view of a device constructed in accordance with my invention. Fig. 2 is a longitudinal section therethrough as seen on line 2—2, Fig. 1. Fig. 3 is a transverse section therethrough as seen on line 3—3, Fig. 1. Fig. 4 is a detail transverse section through the device disclosing the connection between the side longitudinal draw bars and the rear rigid bar of the device. Fig. 5 is a vertical section therethrough as seen on line 5—5, Fig. 4. Fig. 6 is a detail perspective view 35 of the sleeve connection shown in Figs. 4

and 5. Fig. 7 is a detail perspective view showing the connection between a tooth bar of the longitudinal draw bars. Fig. 8 is a similar view showing the connection between one of the levelers and a longitudinal draw bar. Fig. 9 is a sectional perspective view showing the means of connection between the sections of the tooth bars. Fig. 10 is a similar view showing the connection between the leveler sections. Fig. 11 is a detail perspective view of one of the tooth bars showing the manner of retaining a tooth in position thereon. Fig. 12 is a bottom plan view showing the hinge connection between the sections of the transverse draw bar. Fig. 13 is a section therethrough; and Fig. 14 is a diagrammatic view partly in section showing the relation of the longitudinal draw bars with respect to one another on the rigid transverse bars at the rear end of the device.

In describing my invention, I shall refer to the drawings in which similar reference characters designate corresponding parts throughout the several views and in which—

1 indicates a transverse channel bar, the channel portion of which is faced downwardly, said bar having a pair of arms or rods 2 secured thereto and extending rearwardly thereof, and secured to the rear ends of the rods or bars 2, is an additional transverse bar 3. These members 1, 2 and 3 form substantially a frame for the rear end of my improved device and mounted to oscillate 80 between the bars 1 and 3 on horizontal axes, as indicated at 4, are the frames 5 within which are rotatably mounted the rollers 6. These frames with the rollers therein are 85 disposed on opposite sides of the longitudinal connecting rods or arms 2 between the bars 1 and 3 and are designed for a purpose to be hereinafter and more particularly set forth.

90 Disposed in spaced relation, forward of the bar 1, is a main transverse draw bar 7, which is formed in sections and hinged one to the other as shown at 8 and connected to the outer ends of the sections of this bar 7, are the longitudinal draw bars or rods 9, 100 said latter rods or bars having direct connection with the bar 7 through a link con-

nection indicated as 10. These longitudinal bars 9 are, as stated, connected with the outer sections of the draw bar 7 and connected with the intermediate section of the 5 main draw-bar 7, through the medium of a link connection indicated as 11, are a plurality of additional draw bars or rods 12 arranged in pairs.

Connected to the longitudinal draw bars 10 9 and 12, in a manner to be hereinafter set forth, are a plurality of tooth bars 13. These bars traverse the path of the main frame and are of similar construction. Each 15 consists of four sections 13^a, 13^b, 13^c and 13^d which are freely connected to each other by rings 15 or equivalent fastening devices which are engaged in the terminal bracket 14. The sections of each bar are arranged to define two adjoining V's which are trans- 20 versely alined and are disposed with their apexes on opposite sides of the center of the cutter. The space between the apexes or points of the V's is approximately equal to the standard wheel tread of wagons, buggies 25 or similar vehicles. Thus it will be seen that the opposed outer bars of each V will scrape the dirt from the sides of the road and direct it inwardly toward the ruts which are ordinarily present in roads, while the opposed inner sections of the two V's will scrape the dirt from the center of the road and between the ruts and direct it outwardly to the ruts. In this manner my grader will efficiently act 30 to level the road and fill the wheel ruts. It 35 is now to be noted that the corresponding sections of the several bars 13 are arranged in alinement with each other and in parallel spaced relation so that the action of the first bar is duplicated by all of the succeeding bars. 40 These tooth bars which are formed of angular metal, facing forwardly, have one angular face thereof provided with a plurality of notches in which are disposed the narrow teeth 16, said teeth resting against blocks or the like 17 held within the faces of said bars and U-shaped clamping members 18 extend 45 through said blocks and through one face of the bars to clamp said teeth in position, as clearly shown in Fig. 11 of the drawings. 50 Through this medium, the teeth may be readily adjusted, with respect to the bars 13, as desired.

As above stated, the bars 13 are connected to the longitudinal bars 9 and 12 and in carrying out this idea, angular plate-like members 19 are secured to the bars 13 at predetermined points thereon, each of said plate-like members being provided with an angular arm 20 which extends above and below the faces of the bars. The upper end of this arm 20 is pivotally connected, as indicated at 21 to the longitudinal rod or bar, while the lower end thereof has loose connection with a linking member 22. This link-

ing member is in turn adjustably connected, 65 as shown at 23, with the longitudinal rod or bar to which the arm 21 is pivotally connected and at a point forward of said pivotal point. The connection between the bars 9 and 12 and the bars 13, is the same and it 70 will be seen that through the medium of this connection described and clearly shown in Fig. 7 of the drawings, the tooth bars may be adjusted to dispose the teeth carried thereon to various angles, whereby the earth 75 may be engaged in various ways desired.

Disposed rearwardly of the plurality of tooth bars 13, are the leveling members 24 which are also arranged in sections hinged one to the other, the sections of which are 80 disposed angularly to one another and parallel to the respective sections of the tooth bars. These leveling members are formed of angular metal, the angle facing rearwardly and the depending face thereof being of greater 85 length than the horizontal face thereof, as shown in Figs. 8 and 10 of the drawings. Secured to the upper ends of the sections are the angular brackets 25 which are connected together by means of the ring member 90 26, thus providing a loose connection between the sections of the levelers.

Secured to the upper portions of the sections of the levelers, at predetermined points 95 thereon, are the angular plate-like members 27 similar to the plate members 19, but facing oppositely thereto. These plate-like members 27, are also each provided with an inclined arm 28 extending above and below the horizontal face of the levelers and the 100 upper end thereof is pivotally connected as shown at 29 to the adjacent longitudinal bar. The lower end of the arm 28 is loosely connected to a linking member 30, said latter member being adjustably connected, as the 105 link 22, to said longitudinal bar, but forward of the pivot point of the arm 28. This construction is substantially the same as the construction shown and described in connection with the tooth bars and it will be seen 110 that through this medium, the levelers may be adjusted with respect to the longitudinal bars to be disposed at various angles with respect thereto.

Loosely connected to the bar 1, as indicated at 31, at points adjacent the ends of said bar, are the arms 32, which are inclined downwardly and outwardly. The rear ends of the outer longitudinal draw bars or the like 9, are loosely connected to these arms 32, 120 at points indicated as 33. Loosely disposed through the bar 1, adjacent its ends, are the sleeve-like members 34 and rods or the like 35 extend therethrough, the lower ends of said rods being loosely connected to the outer 125 ends of the outwardly and downwardly inclined arms 32. Encircling the rods 35 between the arms 32 and the lower ends of

the sleeve-like members 34, are the coil springs 36 and the upper ends of said rods 35, which project above the sleeves 34, are threaded and have the nuts 37 engaged therewith.

A pair of shafts 38 are mounted for oscillation in bearings 39 on the bar 1, the inner opposed ends of said shafts terminating at points on opposite sides of the longitudinal center of the device and the outer ends of said shafts are provided with crank arms 40. These crank arms having the linking members 41 pivotally connected to the outer ends of the same and the linking members in turn are pivotally engaged with clamping arms 42 which are suitably engaged with the upper ends of the sleeve-like members 34. Through this medium, it will be seen that by the partial rotation of the shafts 38 in one direction, the sleeves 34 may be forced downwardly against the tension of the springs 36, thus forcing the outer ends of the arms 32 downwardly and correspondingly forcing the longitudinal bars or rods 9 downwardly. The actuation of the shafts 38 is through the medium of the levers 43, which are suitably engaged with the inner opposed ends of said shafts, as clearly shown in Figs. 1 and 3 of the drawings.

While the outer longitudinal draw bars 9 have a more or less direct connection with the rear rigid bar 1, the longitudinal bars 12, on the other hand, terminate slightly in advance of said bar 1, as clearly disclosed in Fig. 2 of the drawings. It must here be stated that said longitudinal bars 12 are offset intermediate of their ends, as indicated at 44 and, in this manner the rear portions of said bars, to which the levelers 46 are connected are in a plane slightly above the plane of the forward portions of the bars carrying the tooth bars. Carried on each of the bars 12, forward of the offset portion 44 thereof, is an upstanding projection 45 to which is pivotally connected the forward end of an arm 46, the latter extending rearwardly above and in alignment with said bars 12. The rear portions of the bars 12 have pivotal connection with the arms 46 through the medium of the vertical connecting arms 47.

There are, as shown in the drawings, two pairs of longitudinal bars 12, and the arms 46 connected with the outer of said bars 55 have their rear ends pivotally connected to crank arms 48, carried on the outer ends of a pair of shafts 49, the latter being mounted for oscillation in bearings on the bar 1, just below the inner ends of the shafts 38. The inner ends of said shafts 49 have levers 50 connected therewith and said shafts may be manually oscillated in their bearings through the medium of said levers whereby to actuate the outer of the pairs of longi-

tudinal bars 12, which cause the tooth bars 65 and leveler sections connected therewith to be forced downwardly into more effective engagement with the surface of the ground.

The bars or arms 46 connected to the inner longitudinal bars 12 have their rear ends 70 pivotally connected with a pair of additional crank arms 51 which are carried on the ends of an additional shaft 52 mounted for oscillation in bearings about centrally of the bar 1. A lever 53 is connected to this shaft 52 whereby said shaft may be oscillated in its bearings to actuate the inner longitudinal bars 12, for effecting the same result as described in connection with the operation of the aforesaid levers 50. 80

Secured to the central portion of the bar 1 and extending upwardly and rearwardly therefrom, is a seat post 54, upon the outer end of which is mounted a seat 55 and this seat is disposed adjacent the levers 43, 50 85 and 53, so that the latter may be readily grasped and actuated by the driver of the device. Suitably connected to the central portion of the transverse draw bar 7, are the linking members 56, to which may be 90 suitably connected draft devices for drawing the drag over the surface of the ground.

In practice, this device is particularly adapted for use in connection with rural roads which are in extremely poor condition 95 and where deep tracks and gullies are formed through the constant driving of wagons and other vehicles in particular portions of the road. In order to grade roads of this character, a particular construction must be provided which will remove the surface of the ground on both sides of these gullies, which have been formed, and apply the same to the gullies or tracks and at the same time smoothing the roads so formed. 100

In order to accomplish this result, I have provided the tooth bars and levelers in sections which are connected together and each section successively disposed at an angle with respect to the other. The corresponding sections of the tooth bars, as clearly disclosed in Fig. 1 of the drawings, converge in longitudinal lines which approximately coincide with tracks or gullies formed in the road and as the intermediate sections of the tooth bars and levelers are directed rearwardly and outwardly, and as the outer sections thereof are directed downwardly and outwardly, it will be seen that as the device is propelled, the soil between the tracks or gullies, may be removed and directed toward said tracks, while the soil outside of the tracks and gullies may be directed inwardly toward the same. In this manner the tracks will be filled up to the level of the other portions of the roads and the leveling bars 24 will smooth the soil so placed to an appreciable extent. The rollers 110

115

120

125

6 follow the levelers at the portions where the tracks were previously formed and thus pack the soil tightly at such points.

As the roads are usually formed convexly, 5 so as to effectively turn the same, I have constructed my device accordingly. The draw bar 7 is formed in sections so that the outer end sections thereof may be dropped somewhat downwardly according to the 10 curvature of the roads and the tooth bars and leveler sections are loosely connected together to compensate for this curvature. The rollers, being carried in frames, which are mounted for oscillation, may readily 15 conform to this curvature, and the position of the parts of the device with respect to one another when the device is in use can be readily observed from the showing made in Fig. 3 of the drawings. It will, of 20 course, be understood that the positions of the leveler sections and tooth bars with respect to the longitudinal bars may be adjusted as desired, through the adjusting links 22. In the operation of the device, it 25 will be seen that in view of the particular yielding connection at the outer ends of the device, at which points obstructions are most liable to be made, the device will readily yield to any such obstructions found 30 in the path of travel of the device. Should it be desired to force the harrow teeth and the levelers into more effective engagement with the surface of the ground, it is only necessary for the operator of the device to 35 properly actuate the levers 43, 50 and 53, which will obviously actuate the longitudinal draw bars 9 and 12 to accomplish the desired result.

Particular attention is now directed to 40 the fact that the members 9 and 12 constitute, in reality, not only a means for independently adjusting the elevation of each end of each of the bar sections of the several longitudinal series of sections, but that they 45 also constitute draft rods, whereby the grader is drawn over the ground.

From the foregoing it will be seen that I 50 have provided a simple, inexpensive and efficient means for carrying out the objects of the invention and while I have particularly described the elements best adapted to perform the functions set forth, it is obvious that various changes in form, proportion and in the minor details of construction may 55 be resorted to without departing from the spirit or sacrificing any of the principles of the invention.

Having thus described this invention, what 60 I claim is:—

1. A road drag including a main frame, draft rods extending forwardly from the frame in parallel spaced relation to each other, a transverse draft bar connected to the forward ends of the rods, a plurality of

bars supported by the rods, ground treating implements carried by the bars, and means mounted upon the main frame for independently adjusting the several draft rods, whereby the elevation of the ground treating implements may be varied. 65 70

2. A road drag including a main frame, draft rods extending forwardly from the frame in parallel spaced relation to each other, movable crank arms connecting the rear ends of the draft rods to the main 75 frame, a transverse draft bar connecting the forward ends of the draft rods, a plurality of bars carried by the draft rods, ground treating implements carried by the bars, and means mounted upon the main frame 80 and connected to the crank arms for adjusting the draft rods, whereby the elevation of the ground treating implements may be controlled.

3. A road drag including a main frame, a 85 plurality of draft rods extending forwardly from the main frame in parallel spaced relation to each other, movable crank arms connecting the rear ends of the draft rods to the main frame, adjustable means controlling the position of the crank arms, for retracting the draft rods or projecting them, and a plurality of ground treating implements carried by the draft rods, the elevation of the ground treating implements, with 90 respect to each other being controlled by the 95 said adjustable means.

4. A road drag including a main frame, draft means therefor, a plurality of ground treating implements, and a plurality of 100 bars supporting the implements, said bars being disposed in advance of the main frame, each of said bars consisting of a plurality of freely connected angularly related sections arranged to define two forwardly 105 opening V's, which lie on opposite sides of the center of the drag and are adapted to cause the ground treating implements to direct the dirt on the road, outside of the ruts therein, inwardly toward the ruts and the dirt in the center of the road between the ruts, outwardly toward the ruts. 110

5. A road drag including a main frame, a plurality of ground treating implements, and a plurality of bars carrying the implements, said bars being disposed in advance of the main frame, each of said bars consisting of four freely connected sections, said sections being arranged to define two transversely spaced, forwardly opening V's, the apexes of which are adapted to move along the road over the ruts therein, whereby a diagonally disposed section is located on each side of each rut, for scraping the dirt from the sides of the road and from the center portion thereof and directing it into the ruts. 115 120

6. A road drag including a main frame, a

plurality of ground treating implements, and a plurality of bars carrying the implements, said bars being disposed in advance of the main frame, each of said bars consisting of four freely connected sections, said sections being arranged to define two transversely spaced, forwardly opening V's, the apexes of which are adapted to move along the road over the ruts therein, whereby a diagonally disposed section is located on each side of each rut, for scraping the dirt from

the sides of the road and from the center portion thereof and directing it into the ruts, the corresponding sections of the several bars being arranged in parallel relation to each other. 15

In testimony whereof I hereunto affix my signature in the presence of two witnesses.

EDWARD E. BARRETT.
